UNITED STATES PATENT OFFICE.

CLIFFORD ROBERT STEPHEN JOHN HALLÉ, OF LONDON, ENGLAND.

AUTOMATIC FIREARM.

1,010,899.

Specification of Letters Patent.

Patented Dec. 5, 1911.

Application filed June 17, 1911. Serial No. 633,770.

To all whom it may concern:

Be it known that I, CLIFFORD ROBERT STEPHEN JOHN HALLÉ, a subject of the King of Great Britain, residing at London, England, have invented certain new and useful Improvements in or Connected with Automatic Firearms, of which the following is a specification.

This invention relates to automatic small-arms for sporting and other purposes of the type in which a portion of the powder gas is taken from the barrel during the flight of the bullet down the barrel and used for the purpose of compressing a spring or air, the power thus stored being utilized for the purpose of working the mechanism subsequently to the bullet having left the barrel and the gas pressure being relieved.

In order that the return or cocking spring may be of ample power, and that what is usually termed the main spring may not have to do the double work of opening the breech and at the same time compressing the return spring, the present invention provides mechanism whereby both the opening and return springs are compressed simultaneously and directly by the action of the single plunger on which the gases act. This renders the spring mechanism generally simple and compact and besides the advantage already specified it can be so arranged that the functioning of the weapon can be delayed at the will of the firer, so that the weapon, although always ready to unload and reload itself automatically, when fired, will not do so until a button is pressed by the firer.

In order that when worked by hand, the weapon may function in the same manner as an ordinary magazine rifle, I have devised means whereby the automatic spring mechanism is thrown out of operative relation with the bolt, whenever the knob of the handle is lifted, and is thrown into operative relation again immediately the handle knob is turned down. The handle itself has been made separate from the bolt and lying alongside of the bolt in a separate tube. Besides throwing the automatic mechanism into gear when the knob of the handle is turned down, the turning of the knob frees the handle from the bolt, which is therefore able to fly back without taking the handle with it, thus enabling the case to

be entirely inclosed and protected from the entry of dirt or sand.

In order to minimize the possibility of corrosion of the plunger tube the usual gas tight plunger has been dispensed with and a loose plunger is provided which is moreover ringed or coned so that the minimum surface thereof may at any time come in contact with the guiding tube as is compatible with its being efficiently guided. In order to be able to do this only the kinetic energy of a certain weight of gas impinging on the face of the plunger which is pressed by the springs against the orifice from which the gas issues is utilized. The gas is allowed to exhaust freely into the air immediately after impact on the plunger. Lubrication of the plunger at any time may be effected through the large exhaust hole in the tube.

In the annexed drawings illustrating the invention, Figure 1 is a longitudinal sectional elevation of the mechanism. Fig. 2 is an elevation with the wooden stock removed; Figs. 3 to 8 inclusive are detail views, as will be hereafter explained; Figs. 80 9 and 10 are fragmentary views of a fire-arm showing modified arrangements of the catches; Figs. 11 and 12 are detail views of the means employed for locking the plunger head to its tube; Figs. 13 and 14 are fragmentary views of the fire-arm in side elevation and plan view respectively illustrating the handle by which the same may be manipulated manually; and Figs. 15 and 16 are detail views showing the lever for locking the bolt sleeve in open position.

a is the barrel, which has, as close to the muzzle as convenient, a cone shaped projection *a'*. Through this projection there is a hole of a size sufficient to permit the passage of the required amount of the powder gases. The projection is tapped for a screw. In rear of this cone *a'* is a tube *h*, which is connected to the said cone by means of a socket member *h'*. This socket member is 100 perforated to take the threaded locking pin *j*, and is coned at the top to fit over the cone *a'*, the upper end of the pin *j* being engaged in the threaded portion of the cone. It is evident that when the coned portion of the 105 socket member *h'* is placed on to the cone *a'*, and the pin *j* is screwed into *a'* the joint is gas tight and firm.

The pin j is formed with a passage communicating at its upper end with the hole in the barrel, and at its lower end with the hole h^2 in the socket member h' . Thus, 5 when the thumb piece of j is pointed to the muzzle as at Fig. 1, direct communication is established through the pin between the barrel and the tube, but when the thumb piece is turned to the opposite direction, 10 communication between the barrel and the tube is cut off and the gas exhausts freely into the air from the tube in the front of the stock. This arrangement simplifies the stripping of the weapon, as it will be evident that by unscrewing the pin j the tube can easily be slipped off the gun.

Inside the tube h there is a loose plunger g^2 , which forms the end of the tube g . The other end of the tube g is shaped as shown 20 at g' , viz., with a thickened rim projecting back, and having a bevel at the side for the purpose of engaging with one catch and releasing another catch in its travel. This tube g telescopes over the end of another 25 tube f , which is screwed into the body of the rifle, as shown. There are springs f^3 and g^3 in these tubes which compress as the tubes telescope. The plunger g^2 is screwed on to the solid end of the tube g 30 and is prevented from turning by a washer g^4 which is fitted over the threaded end of the tube g and has a flattened side g^5 which engages a plane surface g^6 on such tube, a pin g^7 locking the washer to the plunger g^2 . 35 The driving rod l is fashioned as shown in Fig. 2 and Fig. 3, viz.: It is a flat bar, with a broad ring l' at the side, which ring slides loosely on the tube g and between this ring and the plunger head there is the 40 spring s^2 . The ring l' is capable of rocking on the tube so as to give the rear end of the driving rod a certain amount of vertical play. The driving rod has a claw l^8 which engages with a downward projection d' 45 from the bolt sleeve d . It also has a nick l^5 in which the catch m normally engages. It has a claw piece l^2 in which the end of the lever o , Fig. 8, engages. It also has a projection l^4 at the side, which runs in a 50 guiding slot in the body of the rifle. k is a simple spring catch attached to the body of the rifle side by side with the catch m , the catches k and m being fixed to and turnable with a common pivot. In the under 55 side of the tube h there is a large opening h^3 to allow of the gases exhausting freely into the air immediately after their impact has shot the plunger forcibly against the springs f^3 and g^3 . The amount of gas required 60 for the functioning of the weapon is such a small proportion of that generated by the discharge that an amount far in excess of what could possibly be required could be taken without in any way affecting the 65 velocity of the bullet.

In Fig. 1 the mechanism is so arranged that the rifle will function automatically at each discharge. The cycle of movement is as follows: When the gases impinge upon the plunger the latter is shot down the tube h , thus compressing the springs f^3 and g^3 contained in the tubes f and g . These tubes telescope, and as the driving rod l is held from rearward movement by the catch m the tube g shoots as it were through the ring l' , thus compressing the spring s^2 between the plunger head and the ring l' . At the end of its travel the shaped head g' of the tube g depresses and passes the catch k , the bevel of the head g' on the end of the tube g thereby releasing the catch m , the head g' becoming locked by the catch k . The driving rod l is thus free to travel and pushes back the bolt sleeve—thus unlocking the breech and extracting the cartridge shell. When the bolt has almost reached the back of the gun the ring l' reaches the catch k and causes it to release the head g' , thus setting free the springs f^3 and g^3 80 contained in the tubes f and g . These springs then expand, and the tube g carries forward the driving rod to its original position, thus loading a new cartridge and cocking the gun—the cocking being effected by the firing pin catching on the sear p as the bolt 90 travels forward.

For military purposes it might be thought desirable to delay the functioning of the mechanism with a view to preventing waste of ammunition and facilitating fire drill. This modification is shown in Fig. 9 a thumb piece m' being attached to the catch m^2 and the inclined plane on the rear of the tube g is omitted. The catch m^2 will remain locked until the thumb piece m' has been depressed, when the rifle will automatically eject the empty shell and load a fresh cartridge. The rifle can also if desired be so constructed as to work at will either automatically, or as last described, such a construction being shown in Fig. 10. The inclined plane on the rear of the tube g is employed in this instance, but an extra catch m^3 is arranged in front of the catch m^4 to engage with the driving rod immediately after the catch m^4 100 has been released. The locking slot m^5 in the driving rod for the hand catch m^3 in this case is a little longer than that for the catch m^4 , so that the end of the slot m^5 reaches the hand catch m^3 just after m^4 110 is released. When this hand catch m^3 moves into position, the automatic mechanism will not function until that catch has been released. If the catch is depressed and kept in the depressed position the mechanism 115 functions automatically at each discharge. The bolt is actuated by the well known device of a sleeve d fitted with a cam working on a projecting pin. This sleeve is, however, made with a downward projection d' 120

on the left side and a slot d^2 on the right. The downward projection Figs. 4 and 5 engages in the claw of the driving rod, and thus the bolt sleeve is pushed backward and 5 pulled forward by the driving rod.

The handle w , Fig. 7, is not normally attached to the bolt, but is contained in a tube x lying alongside the bolt. This handle w has a projection w^2 near the end, which projection runs along a slot in the containing tube x , and the handle w has also an eccentric projection w^3 at the end; when the handle is forward, and the knob w' turned down, the side projection w^2 is clear of the 15 slot d^2 in the bolt sleeve while the eccentric projection w^3 has forced down the sliding piece t , Fig. 8, thereby depressing the right end of the lever o , the left end of which is in the claw piece of the driving rod l . Thus 20 the driving rod l is pushed up into engagement with the downward projection d' of the bolt sleeve d while the handle w is free. The gun therefore functions automatically without any movement of the handle. If, 25 however, the knob w' of the handle is turned up, the projection w^3 at the front raises the sliding piece t thereby depressing the left arm of the lever o , and pulling the driving rod clear of the bolt sleeve. At the same 30 time the side projection w^2 of the handle enters the slot d^2 in the bolt sleeve and thus becomes attached to the bolt which can then be worked by hand entirely independently 35 of the springs, just like an ordinary straight pull rifle. By turning the knob of the handle down when in the forward position, the gun is placed again in the position for automatic firing. The arrangement of the handle w enables the rifle to be absolutely protected from dust by the cover n in which the bolt operates and this cover need only be removed for the purpose of cleaning the bolt. The trigger and trip piece r and r' are hinged together and function in the known 40 manner of such pieces.

y , Fig. 1, is a safety pin of the usual type, which when turned locks the trigger r .

The magazine calls for no special description. One which contains two rows of cartridges side by side as shown is advisable.

The magazine platform is turned up at the end in the usual manner so as to hold the bolt open when the last cartridge has been fired. The loading is by an ordinary 55 clip, but, in order that the bolt may not fly forward when the platform is pushed down by the cartridges, there is a lever y' pivoted at y^2 on the side of the body. So soon as the firer sees that the bolt is open, he presses 60 in the rear end y^3 of this lever—thus holding the bolt open independently of the platform. After loading, he presses in the front end y^4 of the lever, and the bolt immediately flies forward, when the gun is locked and 65 ready for firing. This lever is also useful

in a case of mis-ejection. Should the spent shell or the new cartridge stick in any way, the firer works the handle and can thus pull the bolt back to the point where the lever will retain it. He then pushes the 70 handle forward and removes the obstructing cartridge. The pressure of the lever will then close the rifle as before.

What I do claim as my invention and desire to secure by Letters Patent is:—

1. In automatic firearms of the character described, the combination of a barrel, breech mechanism for introducing cartridges thereto and extracting shells therefrom, and means for actuating the breech mechanism comprising a cylinder, a piston movable therein and operatively connected to the breech mechanism, a socket member fitted to the forward end of said cylinder and having a bore for conducting gas to the cylinder, the barrel also having a bore for the discharge of gas therefrom, and a pin for maintaining a gas-tight connection between said socket member and the barrel and also having a passage for establishing 85 communication between the bore of the barrel and said cylinder when the pin occupies one position and for discharging gas from the barrel to the atmosphere when said pin is turned into a different position.

2. In an automatic firearm, the combination of a barrel, breech mechanism therefor, and means for actuating the breech mechanism comprising a cylinder, a piston movable therein and operatively connected to the breech mechanism, a socket member fitted to the forward end of said cylinder and having a bore for conducting gas thereto, said socket member also having a conical seat, the wall of the barrel also having a 100 conical projection adapted to engage in said conical seat of the socket member and also provided with a passage leading through said conical projection, and a pin extending through the socket member and threaded 105 into the conical projection on the barrel, said pin serving to secure the socket member in coöperative relation with the barrel and also having a passage for controlling communication between the barrel and said cylinder 110 and the atmosphere.

3. In an automatic firearm of the class described, the combination of a barrel, breech mechanism therefor embodying a breech bolt, a driving rod connected thereto, a spring connected to said rod for opening the breech bolt, means for actuating the breech mechanism comprising a cylinder having a passage for conducting gas thereto from the barrel, the cylinder also having an exhaust port in its wall at a point adjacent to its forward end, a plunger operative upon said spring and engaging loosely in said cylinder so as to be projected 120 rearwardly by the kinetic energy of the gas 125 130

entering said cylinder from the barrel to compress said spring, such gas being exhausted through the exhaust port in the wall of the cylinder when such port is uncovered 5 by the piston, means operative directly on said driving rod to lock said rod from breech opening movement, and means operative to hold said spring under compression after said plunger is projected by the 10 gas to compress said spring.

4. In an automatic firearm of the class described, the combination of a barrel, breech mechanism embodying a breech bolt, a driving rod connected thereto and carrying an 15 operating collar, a reciprocatory plunger operative by gas from the barrel and carrying a tube slidable through said collar and having a controlling head thereon abutting against said collar, a breech opening spring 20 interposed between said plunger and the operating collar on the driving rod, a breech closing spring bearing upon said plunger to restore it to initial position, and a catch operative directly upon said driving rod to 25 lock it from breech opening movement during operation of said plunger to simultaneously compress the breech opening and closing springs.

5. In an automatic firearm of the class described, the combination of a barrel, breech mechanism therefor, and actuating means for the breech mechanism including a reciprocatory bolt, a driving rod for said bolt, said driving rod being adjustable to engage 35 and disengage it with respect to the bolt, a bolt handle for actuating the bolt manually, and means operative by the bolt handle for controlling the operative connection between the bolt and said driving rod.

40 6. In an automatic fire-arm of the character described, the combination of a barrel, a reciprocatory bolt sleeve, automatic mechanism operative by gas from the barrel for actuating the bolt sleeve, a handle separate 45 from the bolt, and means for operatively connecting said handle to the bolt sleeve and for disconnecting the automatic mechanism therefrom to permit manual operation of the bolt sleeve and for disconnecting the 50 handle and connecting the automatic mechanism to the bolt sleeve to permit automatic operation of the bolt sleeve.

7. In an automatic firearm of the class de-

scribed, the combination of a barrel, breech mechanism embodying a breech bolt, a driving rod connected thereto and carrying an operating collar, a reciprocatory plunger operative by gas from the barrel and carrying a tube slidable through said collar and 60 having a controlling head thereon abutting against said collar, a breech opening spring interposed between said plunger and the operating collar on the driving rod, a breech closing spring bearing upon said plunger to 65 restore it to initial position, a catch operative directly upon said driving rod to lock it from breech opening movement during operation of said plunger to simultaneously compress the breech opening and closing 70 springs, and a device for retaining both of said springs under compression and operative by said controlling head to disengage said catch and release said driving rod.

8. In an automatic firearm of the class described, the combination of a barrel, breech mechanism embodying a breech bolt, a driving rod connected thereto and carrying an operating collar, a reciprocatory plunger operative by gas from the barrel and carrying a tube slidable through said collar and having a controlling head thereon abutting against said collar, a breech opening spring 80 interposed between said plunger and the operating collar on the driving rod, a breech closing spring bearing upon said plunger to restore it to initial position, a catch operative directly upon said driving rod to lock it from breech opening movement during operation of said plunger to simultaneously 85 compress the breech opening and closing springs, and a device for retaining both of said springs under compression and operative by said controlling head to disengage said catch and release said driving rod, said 90 device being actuated automatically by said collar on the driving rod after the latter has opened the breech to release the compression on said springs and permit closing of the breech.

100 In testimony whereof I have hereunto set my hand in presence of two subscribing witnesses.
